UNITED STATES PATENT OFFICE

OTTO THEUNE, OF BROOKLYN, NEW YORK

CONTROL DEVICE

Application filed January 30, 1930, Serial No. 424,657. Renewed April 4, 1933.

This invention relates to control devices. It is among the prime objects of the present invention to provide a control device particularly adapted for radio receiving apparatus, whereby remote control of the apparatus is provided for.

It is a further object of the present invention to provide in a radio controlling device, a novel and improved indicating structure 10 for indicating the wave length to the station to which the apparatus is tuned.

Another object of the present invention is to provide a radio controlling device particularly adapted to be mounted in conjunction with the instrument panel of an automobile whereby a radio carried by the vehicle may be remotely controlled in a convenient manner from the instrument panel.

Other objects and features of the present invention include a novel and improved combination and interrelation of parts, whereby the whole forms a simple and efficient structure readily designed to meet the demands of economic manufacture.

Other objects of the present invention will be apparent from a consideration of the following specification taken in conjunction with the accompanying drawings, in which

Figure 1 is an elevational view partly in section, as indicated by the dotted line 1—1 of Fig. 2;

Fig. 2 is a vertical section taken on the line 2—2 of Fig. 1;

Fig. 3 is a vertical section looking in the opposite direction and taken on the line 3—3 of Fig. 1;

Fig. 4 is a front view of the radio apparatus showing the method of operating the condensers thereof by the present invention, 40 and

Fig. 5 is a perspective view illustrating the device mounted on the instrument panel of an automobile.

Referring more particularly to the drawings, it will be seen that the present device includes a frame or chassis comprised of an inner vertical base plate 10 joined by a substantially U-shaped bracket 11 with an external interior housing 12. The bracket 11 is 50 adapted to receive therein the lower edge of

the instrument panel board 13, the reinforcing brace 14 of which is adapted to receive adjustable screws 15 carried by the base 10, thus to secure the device in convenient position on the instrument panel, as indicated in Fig. 5.

The indicating structure 12 extends upwardly from the bracket 11 to provide a hollow indicating panel, apertured as at 16, behind the aperture of which a tape 17 bearing suitable wave length or frequency indicia is mounted. The tape 17 passes over an upper roller 18 and extends outwardly and rearwardly from the indicating structure to a drum 19 mounted upon the transverse operating shaft 20 associated with the base 10, as will be hereinafter described. The tape 17 is secured to one end of the drum 19 by a suitable screw 21. The opposite end extends from the indicating structure 12 and passes through an aperture in the drum to be secured by a spring 22 adjacent the axle thereof, the arrangement being such that the spring 22 insures for any slack take up of the tape, whereby it will move accurately at all times with the movement of the drum, to indicate through the aperture 16, the setting of the condensers of the remotely positioned receiving apparatus. Extending through the lower edge of the indicating structure, operating shafts 23 and 24 are provided. The operating shaft 23 may be associated in any desired manner (not shown) with a flexible control device, its outer end terminating in a knob 25, which is preferably used for controlling the volume output of the set. The shaft 24 is also provided with an external knob 26, the turning of which is adapted to control the setting of the condensers of the apparatus by co-operating with the structure carried by the base 10.

The structure supported by the base 10, includes a substantially rectangular bracket 27, the sides of which are apertured to provide journals for the shaft 20. The shaft 24 is provided with a worm gear 28 which co-operates with a gear 29 mounted for rotation with the shaft 20, whereby rotation of the knob 16 will effect a corresponding rotation of the shaft 20, the drum 19 and a second gear 100

30, which gear is mounted on the end of the shaft 20 opposite to the end bearing the drum 19. Associated with the base 10 and the bracket 27, a guide trough 31 is provided, 5 within which a rack 32 is mounted for longitudinal movement, the rack teeth of which are in mesh with the teeth of the gear 30, whereby rotation of the shaft 20 and the gear 30 will cause a corresponding longitudinal 10 movement of the rack 32. The rear end of the rack 32 is adjustably associated by a screw 33 with an operating shaft 34, which may extend through a suitable bearing assembly 35 of the motor board 36 of the vehicle. 15 The bearing structure includes a coupling for uniting the flexible operating cable 37 with the operating shaft 34. It will be understood, of course, that the rack 31 may, if desired, be directly associated with the 20 cable 37.

By this structure, it will be seen that the present device provides means readily attached to the instrument board of the vehicle, whereby the turning of a control knob will 25 longitudinally move a flexible cable. The structure provides improved means for indicating the position of the condensers of an associated apparatus, and further provides a simple and efficient structure applicable to 30 the instrument panel without distortion or cutting thereof, and one which may be readily removed and replaced.

For operating the condensers of the radio apparatus which are indicated in Fig. 4 by 35 the numeral 38, it will be seen that the apparatus end of the cable 37 is provided with a rack 38, movable in a rack drive 39. The main condenser shaft 40 is provided with a gear 41 co-operating with the teeth of the 40 rack 38, whereby longitudinal movement of the cable will move the rack to rotate the shaft 40 by the interconnection therebetween of the cable 41.

The apparatus 30 is indicated as having a 45 plurality of condensers arranged for gang movement by suitable connecting belts 42. It will be understood, however, that the present invention is not confined to this structure and any equivalent arrangement may be 50 used.

It is also indicated in Fig. 4, that the shaft 23 is adapted for co-operation with the cable 43, whereby the volume control of the apparatus may be controlled by rotation of the cable 55 in response to rotation of the shaft 23. The cables 43 and 37 are, as indicated, preferably armored cables, whereby they are not liable to interfere due to the extension of these cables to a remotely positioned apparatus.

60 In connection with the present invention, it will be understood that the device is not confined to the specific detail structures herein presented, but that numerous changes, modifications, and the full use of equivalents 65 may be resorted to in the application of the

invention without departing from the spirit or scope of the appended claims.

What is claimed is:

1. A control device of the class described comprising a supporting structure adapted to be secured to the lower edge of a suitable support and having a hollow front panel for disposition in front of the support, an indicating tape, means carried by said structure mounting the tape for movement, said means being of such character that two leads of the tape may pass beneath said support into said front panel through its lower end, said front panel having a sight opening therein so that a portion of the tape will be visible, and means carried by said structure which operates with the first mentioned means to control the movement of the tape. 70

2. A control device of the class described comprising a supporting structure adapted to be secured to the lower edge of a suitable support and having a hollow front panel for disposition in front of the support, an indicating tape, means carried by said structure mounting the tape for movement, said means including a rotatable drum at the rear of said front panel and of such character that two leads of the tape may pass beneath said support into said front panel through its lower end, said front panel having a sight opening therein so that a portion of the tape will be visible, and means carried by said structure which is operatively connected with said drum to rotate it to control the movement of the tape. 80
